(57) **CLAIM**

The ornamental design for a set of earphones as shown and described.

DESCRIPTION

FIG. 1 is a front perspective view of a set of earphones according to the invention.

FIG. 2 is a front view of the set of earphones of FIG. 1.

FIG. 3 is a rear view of the set of earphones of FIG. 1.

FIG. 4 is a right side view of the set of earphones of FIG. 1.

FIG. 5 is a left side view of the set of earphones of FIG. 1.

FIG. 6 is a top plan view of the set of earphones of FIG. 1.

FIG. 7 is a bottom plan view of the set of earphones of FIG. 1; and,

FIG. 8 is a bottom perspective view of the set of earphones of FIG. 1.

1 Claim, 7 Drawing Sheets
